LENS FOR VEHICLE MARKER LAMP OR THE LIKE

Donald S. Bruce, Holliston, Mass., and John B. Dickson,
Kew Gardens, N.Y., assignors to Signal-Stat Corporation,
Brooklyn, N.Y., a corporation of New York

Filed Apr. 4, 1960, Ser. No. 60,025

Term of patent 7 years

(Cl. D48—32)

FIG.1

FIG. 2

FIG.4

FIG. 3

FIG. 1 is a side elevational view of a lens for vehicle marker lamp or the like, embodying our new design;

FIG. 2 is a front elevational view thereof;

FIG. 3 is a bottom plan view thereof; and

FIG. 4 is an enlarged rear elevational view thereof.

We claim:

The ornamental design for a lens for vehicle marker lamp or the like, as shown.
